UNITED STATES PATENT OFFICE.

ROBERT BROWN, OF GLASGOW, SCOTLAND.

APPARATUS FOR PROMOTING THE CIRCULATION OF WATER IN STEAM BOILERS.

Application filed July 21, 1923. Serial No. 653,015.

To all whom it may concern:

Be it known that I, ROBERT BROWN, of 76 Barfillan Drive, Cardonald, Glasgow, Scotland, a subject of the King of Great Britain, have invented certain new and useful Improvements in Apparatus for Promoting the Circulation of Water in Steam Boilers, of which the following is a specification.

This invention relates to apparatus for promoting the circulation of water in steam boilers, the apparatus being of the type which is adapted to be contained wholly within the boiler and to be operated without the use of means external to the boiler in which it is contained.

One of the objects of the present invention is to provide an apparatus which shall come into operation much more rapidly than has heretofore been possible; a further object is to provide an apparatus which shall be of simple construction and which may be readily fitted to or detached from a boiler.

According to the present invention the parts of the apparatus are so constructed and arranged that a primary local circulation is set up before the main circulation can be set up to discharge water, as usual, from the apparatus above the water level of the boiler.

The primary local circulation commences very rapidly after the lighting of the boiler fires and long before the said main circulation is possible, and will continue when the fires are banked and the heat generated is insufficient to maintain the said main circulation.

The invention, including certain details of construction and combinations of parts, will now be described as embodied in a water-circulating apparatus suitable for use with a marine boiler, but it is to be understood that this is by way of exemplification and not of limitation.

In the accompanying drawings:—

Fig. 1 is an end sectional elevation of a marine boiler having the apparatus in place;

Fig. 2 is a side sectional elevation of part of the boiler shown in Fig. 1;

Fig. 3 is a view similar to Fig. 1 but showing a modified form of apparatus;

Fig. 4 is an elevation of the bell mouthed collector; and

Fig. 5 is a plan of the parts shown in Fig. 4.

Referring to Figs. 1 and 2, the boiler 1 of the usual marine type has three furnaces

2 and three nests of tubes 3. The water circulating apparatus is indicated generally as A and comprises a circulator tube 4 in the water space between adjacent nests of tubes. 60 It is secured to the stay rods of the boiler at 5 and 6, by clamps 8 and 9. The circulator tube 4 is sufficiently long to extend well into the steam space 11 of the boiler, 65 and is closed by a cap 12 to resist leakage of air or steam. The lower end of the circulator tube 4 ends in a collector 13 for the rising water, which collector is located closely adjacent to the crown of a furnace so as to be in the path of the rising water when 70 the boiler is heated. If the crown is corrugated the end of the collector should be shaped to correspond.

A branch 14 of the tube 4 extends from 75 well below the water line to a point just above the working water level, its upper or discharge end being formed as a goose-neck 15.

A dip pipe 16 is secured at 7 by a clamp 80 10 to a boiler stay rod. The upper end of the dip pipe leads into the collector 13 and forms a nozzle 17, while the lower end carries a strainer 18 which is located in the dead water space.

In the construction shown in Fig. 3 the 85 circulator tube 4 ends in a fork 19 each branch of which ends in a collector 13^a. Each collector is located close to an adjacent furnace crown.

It will be noted that the upper closed 90 portion of the circulator tube 4 forms a chamber 20 in which air or steam or both is imprisoned between the cap 12 and the water in the tube. Also, the branch 14 is 95 of much smaller diameter than the tube 4.

The collector 13 may be made of zinc or may be zinc lined in which case some or all of the usual zinc plates in the boiler may be dispensed with.

It will be seen that with the present construction the apparatus will not become air or steam bound.

Operation:—

When the furnaces are fired the water in 105 the confined space of the collector 13 circulates much more quickly than in the boiler and this local circulation quickly induces a flow of cold water from the dip pipe 16 into the circulator tube 4. It is found that even if the fires are banked, a small local circulation takes place from the dead water space.

As the heat of the general body of water adjacent to the furnace crown increases, steam is formed and enters the collector 13 thus increasing the rate of circulation in the tube 4 until finally the whole of the water in the tube is heated, after which steam will pass up through the heated water into the compression chamber 20. As a result, the water in the tube 4 is depressed below the general water level of the boiler and the main circulation commences, a constant stream of water being discharged from the goose-neck 15.

As soon as the discharge commences from the branch 14 an increased suction effect is produced upon the nozzle 17 and a more rapid flow from the dead water space results.

This action continues whilst steam is being raised; if the fires are banked there will still be the local circulation as at first described, and this will continue so long as there is the necessary difference in temperature between the water adjacent to the collector 13 and the water in the dead water space.

The theory of operation is as follows:

Owing to the size of the collector, the steam above the water level in the tube 4 would be greater in amount than the steam above the rest of the water per unit of area; since this steam would be confined in the comparatively long narrow projection of the tube above the water level it would be unable to spread out immediately with the consequence that the pressure within the open upper end of the tube would be slightly greater than the general pressure in the steam space. Consequently, the water in the tube 4 would be slightly depressed below the general water level and as a consequence would lift the water in the branch 14 above the general water level since the slight excess pressure would be operating upon a very much smaller area in the branch 14.

Regarding the closed top construction, the pressure in the upper part of the tube 4 will, after a short time, become fairly considerable since the amount of steam collected by the collector will be so much greater per unit of area than the steam rising to the general surface. As a consequence, the water level in the tube 4 will be depressed considerably below the general water level of the boiler with the result that this excess pressure acting upon the small area of the branch 14 would cause the water in the latter to rise considerably above the general water level; as, however, the branch 14 rises only a small amount above the general water level, the water therein is discharged and is discharged in a constant stream and not a pulsating stream.

Owing to the large area of the collector in comparison with the area of the tube 4,

the amount of steam collected would normally be sufficient to raise the water in the tube considerably above the temperature of the water in the rest of the boiler and the excess amount of steam is apparently sufficient to warm the water drawn up by the dip pipe to an adequate extent. It will be noticed that the area of the dip pipe is in its turn very much less than the area of the tube 4. The same arguments would seem to apply before the boiler was actually producing steam, the collector permitting a comparatively large quantity of heated water to rise into the tube 4.

It will be appreciated that such an apparatus is very simple, and may be readily put in place. Further, it comes into action very quickly after the boiler fires are lighted and continues when the fires are banked and the heat generated is insufficient to maintain the main circulation.

Having now fully described my invention what I claim and desire to secure by Letters Patent is:—

1. Water circulating apparatus for a steam boiler which is contained wholly within the boiler and is operated without the use of means external thereto, comprising a circulator tube having an open end located immediately adjacent and opening toward the crown of a furnace at the point of maximum initial heat, the upper end of the circulator tube extending into the steam space of the boiler and being closed, a branch from the circulator tube opening into the steam space, and a dip pipe extending from the dead water space of the boiler into the open end of the circulator tube and being of less diameter than such open end of the tube.

2. Water-circulating apparatus for a steam boiler which is contained wholly within the boiler and is operated without the use of means external thereto comprising, in combination, an open-mouthed flared collector opening toward and located immediately adjacent the crown of a furnace at the point of maximum initial heat, a dip pipe extending upwardly from the dead water space into the collector and passing thereto, a circulator tube leading upwards from the collector into the steam space of the boiler, the upper end of the circulator tube being closed and a branch therefrom also leading upwards into the steam space.

3. Water-circulating apparatus for a steam boiler which is contained wholly within the boiler and is operated without the use of means external thereto comprising, in combination, an open-mouthed flared collector opening toward and located immediately adjacent the crown of a furnace at the point of maximum initial heat, a dip pipe extending upwardly from the dead water space into the collector and passing thereto.

into, a circulator tube leading upwards from the collector into the steam space of the boiler, the upper end of the circulator tube being closed and a branch therefrom also 5 leading upwards into the steam space, said branch being shorter than said circulator tube.

4. Water-circulating apparatus for a steam boiler which is contained wholly 10 within the boiler and is operated without the use of means external thereto, comprising an open-mouthed flared collector opening toward and located immediately adjacent the crown of a furnace at the point 15 of maximum initial heat, a dip pipe extending upwardly from the dead water space into the collector and passing thereinto, a circulator tube leading upwards from the collector into the steam space of the boiler, 20 the upper end of the circulator tube being closed and a branch therefrom of smaller sectional area than the circulator tube also leading upwards into the steam space, the dip pipe being of smaller sectional area than 25 the circulator tube.

5. Water-circulating apparatus for a steam boiler which is contained wholly within the boiler and is operated without the use of means external thereto, comprising an 30 open-mouthed flared collector opening toward and located immediately adjacent the crown of a furnace at the point of maximum initial heat, a dip pipe extending upwardly from the dead water space into the collector and passing thereinto, a circulator tube leading upwards from the collector into the steam space of the boiler, a fluid-tight cap upon the upper end 35 of the said tube, and a branch from the

circulator tube also leading upwards into 40 the steam space.

6. Water-circulating apparatus for a steam boiler which is contained wholly within the boiler and is operated without the use of means external thereto, comprising 45 an open-mouthed flared collector, located with its mouth close to a furnace crown of the boiler, a dip pipe extending upwardly from the dead water space into the collector and passing thereinto, a circulator tube leading 50 upwards from the collector into the steam space of the boiler, the upper end of the circulator tube being closed and a branch from the circulator tube of smaller sectional area than the circulator tube also leading upwards into the steam space, the dip pipe being of smaller sectional area than 55 the circulator tube.

7. Water-circulating apparatus for a steam boiler which is contained wholly 60 within the boiler and is operated without the use of means external thereto, comprising an open-mouthed flared collector, located with its mouth close to a furnace crown of the boiler, a dip pipe extending upwardly 65 from the dead water space into the collector and passing thereinto, a circulator tube leading upwards from the collector into the steam space of the boiler, a fluid-tight cap upon the upper end of the said tube, and a branch from the circulator tube also leading 70 upwards into the steam space.

In testimony whereof I affix my signature in presence of two witnesses.

ROBERT BROWN.
